UNITED STATES PATENT OFFICE

RUDOLPH J. SAILER, OF ELIZABETH, NEW JERSEY, ASSIGNOR TO THE SINGER MANUFACTURING COMPANY, OF ELIZABETH, NEW JERSEY, A CORPORATION OF NEW JERSEY

FOLDER FOR SEWING MACHINES

Application filed February 8, 1929. Serial No. 338,393.

This invention relates to improvements in folders for sewing machines and more particularly to hem-folders of the type having folder-sections which are separable to provide for the completion of endless hems in circular articles of various kinds.

An object of the present invention is to provide a hem-folder of this type with means for accommodating the passage through the folder of work having heavy cross-seams and other lumpy portions. Another object of the invention is to provide for a more convenient manipulation of the work, after the folder-sections are separated, to complete an endless hem. Other and more specific objects of the invention will be apparent from the following description and claims.

In a preferred embodiment of the invention, the folder-sections are supported by a base-plate which is pivotally mounted upon a carrier-bracket for substantially horizontal swinging movement, the carrier-bracket being secured upon a cylinder work-arm of a sewing machine. The outer folder-section, which has the usual concave wall terminating in an overhanging flange, is secured upon the base-plate for adjustment transversely of the line of seam formation. Adapted to abut against the lower edge of said concave wall is a movable or inner folder-section having a concave wall facing that of the fixed folder-section and disposed below the overhanging flange of the latter.

Mounted upon the base-plate, for movement in a direction substantially crosswise of the line of seam formation, is a sliding carrier-block carrying a supporting-plate upon which the inner folder-section is mounted to yield against the action of a suitable spring and relatively to the slide-block. This supporting means for the inner folder-section provides for the passage through the folder of heavy cross-seams and other lumpy portions of the work.

Pivots mounted upon the slide-block is

a latch-lever adapted, in the operative position of the inner folder-section, to engage a fixed stud-pin. This latch-lever projects forwardly beyond the work-receiving end of the folder-sections and has a tripping lip extending into the line of seam-formation, the latch-lever being tripped by the approach to the folder of the initially stitched portion of an endless seam. Bearing against the latch-lever, adjacent its fulcrum, is a spring which not only acts upon the latch-lever to swing it into latching position, but also functions to retract the slide-block to carry the inner folder-section away from the fixed section upon release of the latch-lever. By thus bodily shifting the inner folder-section away from the outer fixed section, ample space is provided for conveniently manipulating the work to finish the hemming operation.

Secured upon the slide-block to overlie the latch-lever is a work-supporting apron which also overlies the inner folder-section and extends into the line of seam formation, whereby said apron assists in guiding the work in the hem-folding operation. This apron is, of course, retractile with the slide-block to open the hem-cavity. The slide-block has suitable connections with a knee-shift or treadle, whereby the retracted slide-block may be conveniently returned to bring the inner folder-section into its operative position.

In the accompanying drawings, Fig. 1 is a front side view in elevation of a portion of a cylinder-bed sewing machine and of the present improved hemming attachment applied thereto. Fig. 2 is a top plan view of the free end portion of the sewing machine work-arm and the hemming attachment, with the work-supporting apron partly cut away. Fig. 3 is a sectional view substantially on the line 3-3 of Fig. 2. Fig. 4 is a bottom plan view of the attachment. Fig. 5 is a detail view, in bottom plan, of the inner folder-section and its support. Fig. 6 is a sectional view sub-

stantially on the line 6—6 of Fig. 1. Fig. 7 is a sectional view substantially on the line 7—7 of Fig. 1. Fig. 8 comprises perspective views of the separated parts of the inner folder-section.

Referring to the drawings, the hemming attachment is shown as applied to a sewing machine having a cylinder work-arm 1, provided with a removable end-cap 2 and a throat-plate 3. Overhanging the work-arm 10 is a bracket-arm terminating in a head 4, in which is suitably journaled a vertically reciprocating needle-bar 5, carrying a needle 6. Also journaled in the head 4 is a presser-bar 7 to which is suitably secured a presser-foot 8 opposed to a feeding mechanism (not shown) of any well known type, provided in the work-arm to advance the work across said arm.

20 The hemming-attachment comprises an angular supporting bracket 9, secured by screws, as 10, upon the work-arm 1 so as to be adjustable in a direction crosswise of the line of seam-formation. Hingedly secured upon the bracket 9, by means of a pivot screw 11 and friction-washer 12, is a hemmer carrier-plate 13 capable of being swung horizontally to remove the hemmer from its operative position. In order to secure the hemmer in its 25 operative position, the carrier-plate 13 is apertured to fixedly receive a hollow post 14 in which is slidably disposed a plunger-type latch-pin 15 adapted to enter an aperture 16 provided in the throat-plate 3. The latch-pin 15 is yieldingly depressed by a spring 17 to an extent limited by the engagement of the head 18 of said latch-pin with the upper 30 end of the post 14.

Secured upon the carrier-plate 13, by 40 screws as 19 so as to be adjustable crosswise of the line of seam-formation, is a hemmer base-plate 20. Adjustably fixed upon the base-plate 20, by screws as 21, is the shank 22 of a primary or outer folder-section 23 of 45 the hemmer. This primary folder-section has a substantially straight edge 24 directly overlying the base-plate and disposed substantially parallel with the line of seam-formation, said edge 24 being in the present case slightly 50 to the right of the seam-line. The primary folder-section rises from said edge 24 in a curved path to form a concave guiding wall 25 terminating in a flange 26, overhanging the wall 25 and crossing the seam-line. The 55 concave wall 25 converges from an outwardly flaring work-receiving end, in advance of the base-plate, toward the delivery end thereof and merges into an edge-guiding finger 27 extending adjacent the presser-foot 8 to a point 60 substantially abreast of the needle 6.

Adapted to abut against the edge 24 of the primary folder-section is a straight edge 28 of a secondary or inner folder-section 29 having a concave wall 30 which constitutes, in 65 effect, a continuation of the wall 25 to form

therewith a folding scroll. The concave wall 30 terminates in an overhanging lip 31 disposed below and spaced from the flange 26, said lip 31 in the abutting position of the edges 24 and 28 of the folder-sections extending across the seam line in a direction toward but spaced from the wall 25.

76 The inner folder-section 29 has a laterally extending shank 32 slidably disposed in a guideway 33 provided in a suitably channeled guide-block 34. The guide-block 34 is secured by screws, as 35, to the under side of a shiftable supporting-plate 36 which is fastened by screws, as 37 and 38 upon a ribbed carrier-block 39. The carrier-block 39 is slidably disposed in a guideway provided by spaced and suitably recessed guide-blocks 40 and 41 secured by screws, as 42 and 43, upon the base-plate 20.

75 Upon the side of the guide-block 34 opposite to that occupied by the inner folder-section 29, the shank 32 of said folder-section carries a transverse abutment-flange 44. Secured upon the under side of the supporting-plate 36, by means of a screw 47, is a wire-spring 48 of which one end bears upon the flange 44 and acts to yieldingly urge the inner folder-section 29 toward the outer folder-section 23. The other end of the spring 48 bears against the shouldered end 45 of the 90 slide-block 39. This yielding feature of the inner folder-section 29 provides for the passage of bulky cross-seams through the hemmer.

95 Extending laterally from the outer end of the supporting-plate 36 is an apertured ear 49 upon which a latch-lever 50 is fulcrumed by means of the supporting-plate securing screw 38. The latch-lever 50 extends in a direction substantially crosswise of the line 100 of seam-formation and at its free end, i. e., at its end nearest the folding scrolls, said latch-lever is provided with a forwardly extending neck 51, terminating in a tripping lip 52 disposed in advance of the folder-sections 105 and crossing the line of seam-formation. Between its ends and on the front edge thereof, the latch-lever 50 is provided with a shouldered latching notch 53, which in the closed position of the folding scrolls is disposed to 110 receive a fixed stud-pin 54, rising from the guide-block 41.

115 Secured upon the latch-lever 50 adjacent its fulcrum, is a plate 55 having a depending ear 56. Bearing yieldingly against the ear 56 is one end of a coiled spring 57 housed within a rectangular casing 58 secured by screws, as 59, upon the base-plate 20. In order to limit the movement of the slide-block 39 and the parts carried thereby in a direction 120 away from the fixed folder-section 23, said slide-block carries a depending stop-pin 60 which engages one end of a slot 61 in the base-plate 20, through which slot the stop-pin 60 extends.

Suitably secured upon the under side of the base-plate 20 are spaced guide-blocks, as 62 and 63, which afford a guideway for a slide-bar 64, having at one end a depending 5 ear 65 adapted to engage the guide-block 63 and at its other end a shoulder 66, positioned to engage the protruding end of the stop-pin 60. The slide bar is yieldingly urged in a direction to cause its depending ear to engage 10 the guide-block 63 by a coiled spring 67 of which one end is secured upon the slide-bar 64 and its other end upon the guide-block 62.

The depending ear 65 of the slide-bar is 15 also engagable by the free end of one arm 68 of a bell-crank lever, fulcrumed by means of a pivot screw 69 upon a fixed arm 70 depending from the supporting-bracket 9. The other arm 71 of said bell-crank lever is connected 20 by a chain 72 or the like with a suitable treadle or knee-shift (not shown) and is also connected by means of a coiled spring 73 with the supporting-bracket 9. The spring 73 obviously functions to hold the arm 68 of the bell-crank lever in a position permitting the 25 spring 67 to return the slide-bar 64 into the position wherein the slide-bar ear 65 engages the guide-block 63.

In order to properly support the body material of which the margin is to be hemmed, there is detachably secured upon the supporting-plate 36, by means of screws, as 74, a covering-plate or work-supporting apron 75. The apron 75 overlies said supporting-plate and latch-lever mechanism, with the 30 exception of the tripping lip 52 of the latch-lever. The inner end 76 of the apron 75 overlies the lip 31 of the inner folder-section 29 and is curved downwardly to conform to the general contour of the folder-sections and 35 thereby facilitate the hem-folding operation.

In a hem-folding operation, the slide-block 39 is latched to occupy its inner position by the engagement of the latch-lever 50 with the 40 stud-pin 54. The necessary forward swinging movement about its fulcrum of the latch-lever into stud-pin-engaging position is effected by the spring 57 which bears upon the depending ear 56 of the latch-lever with an increasing pressure as the slide-block 39 is 45 shifted inwardly by the slide-bar 64, under the action of the treadle-operated lever 68, 71. Under normal hem-folding conditions and in the latched position of the latch-lever 50, the edge 28 of the inner folder-section 29 is urged 50 by the spring 48 into abutting relation with the edge 24 of the outer folder-section 23. However, when lumpy portions of the work, such as cross-seams, pass through the hemmer, the inner folder-section is free to yield bodily 55 laterally in the latched position of the lever 50.

When completing the hemming of endless work, the initially stitched portion thereof engages 60 the lip 52 of the latch-lever 50 and

under the continued feeding of the work carries along the lip 52 in the direction of the line of seam formation, thereby swinging the latch-lever upon its fulcrum until the shoul- 70 dered notch 53 of the latch-lever is disengaged from the stud-pin 54. The latch-lever, with its lip 52, therefore constitutes a work-con- 75 trolled release element for the shiftable folder-section. Immediately upon the release of the latch-lever from the pin 54, the spring 75 80 is free to retract said latch-lever, thereby also retracting the covering-plate 75 and the inner folder-section 29. The stitching opera- 85 tion may now be completed with the fixed folder-section constituting the work-guide. 80 By shifting the inner folder-section bodily away from the outer folder-section, the work may be conveniently manipulated by an operator to complete the hemming operation.

Having thus set forth the nature of the invention, what I claim herein is:

1. A sewing machine having stitch-forming mechanism, in combination with a fabric-folding device having separable sections together forming a scroll for folding a work-margin, supporting means for one of the folder-sections permitting it to yield laterally in a direction away from the other section during the passage of the work through the folding device, and a spring acting automatically during the stitching of endless seams for effecting separation of the folder-sections to provide for the completion of said seams.

2. A sewing machine having stitch-forming mechanism, in combination with a fabric-folding device having separable sections disposed in advance of said stitch-forming mechanism, supporting means for one of the folder-sections permitting said section to yield laterally in a direction away from the other section during the passage of the work through the folding device, a work-controlled release element, and means rendered operative upon the operation of said release element for effecting separation of the folder-sections to provide for the completion of endless seams.

3. A sewing machine having stitch-forming mechanism, in combination with a fabric-folding device having separable sections disposed in advance of said stitch-forming mechanism, supporting means for one of the folder-sections permitting said section to yield laterally in a direction away from the other section during the passage of the work through the folding device, and means automatically brought into effective action during the stitching of endless seams for laterally shifting the yieldable folder-section away from the other section in a direction substantially transverse to the line of seam formation.

4. A sewing machine having stitch-forming mechanism, in combination with a folder including an outer section and an inner section cooperating therewith to hem-fold the margin of a body material, supporting means

- for the inner folder-section permitting it to yield laterally in a direction away from the other section during the passage of the work through the folder, a work-controlled release element, and means rendered operative upon operation of said release element for shifting the inner folder-section away from the outer section to provide for the completion of endless seams.
5. A folder for sewing machines having separable sections together defining a hem-folding cavity, means including a work-controlled release element for releasably latching said folder-sections in hem-folding position, and supporting means for one of the folder-sections permitting it to yield laterally away from the other section in the latched position of said folder-sections.
6. A folder for sewing machines having a fixed section and a movable section together defining a hem-folding cavity, shiftable supporting means for the movable folder-section, means for releasably latching said supporting means in the hem-folding position of the movable folder-section, a work-supporting apron rigid with said supporting means overlying the latching means and extending into the hem-folding cavity, supporting means for the movable folder-section permitting it to yield laterally with respect to the fixed section and said apron during the passage of the work through the folder, and a latch-tripping lip engageable by the initially stitched portion of an endless seam to permit withdrawal of the movable folder-section and said apron from the fixed folder-section.
7. A hem-folder for sewing machines, including an outer section having a concave guiding-wall and an inner section having a concave guiding-wall facing the concave wall of the outer section, means for latching said folder-sections in hem-folding position, and a spring for separating the concave walls of said folder-sections upon release of said latching means.
8. The combination with stitch-forming mechanism, of a hem-folder including an outer section having a concave guiding-wall and an inner section having a concave guiding-wall facing the concave wall of the outer section, means for latching said folder-sections in hem-folding position, a latch-tripping lip located in the line of seam formation, and a spring for separating the concave walls of said folder-sections upon release of said latching means.
9. The combination with stitch-forming mechanism, of a hem-folder including an outer fixed section having a concave guiding-wall and an inner movable section having a concave guiding-wall facing the concave wall of the outer section, means for latching the movable folder-section in its operative position, a latch-tripping lip located in the line of seam formation, automatically acting

means for shifting the movable folder-section away from the fixed section upon release of said latching means, and treadle-connections for returning the movable folder-section into its operative position.

10. A folder for sewing machines having inner and outer sections together defining a hem-folding cavity, a work-supporting apron overlying the inner folder-section and extending into the line of seam-formation, supporting means for one of the folder-sections permitting it to yield laterally during the passage of work through the folder, and means for shifting said work-supporting apron out of the line of seam-formation to provide for the completion of endless hems.

11. A folder for sewing machines having separable sections together defining a hem-folding cavity, supporting means for one of the folder-sections shiftable in a direction substantially crosswise of the direction of passage of work through the folder, a pivotally mounted latch-lever for releasably securing said folder-sections in operative position, and a spring acting upon said latch-lever to swing it into latching position and to shift said supporting means upon release of the latch-lever.

12. A folder for sewing machines having separable sections together defining a hem-folding cavity, supporting means for one of the folder-sections shiftable in a direction substantially crosswise of the direction of passage of work through the folder, a pivotally mounted latch-lever extending forwardly beyond the work-receiving end of the folder and terminating in a tripping lip disposed in the line of seam-formation, and means cooperating with said latch-lever for releasably securing said folder-sections in operative position.

13. A sewing machine having stitch-forming mechanism, in combination with a folder having an outer section and an inner section cooperating therewith to hem-fold the margin of a body material, a carrier-block shiftable in a direction substantially crosswise of the line of seam-formation, supporting means for the inner folder-section permitting it to yield laterally in a stationary position of the carrier-block, means for releasably latching the carrier-block in the operative position of the inner folder-section, latch-tripping means extending into the line of seam-formation, and means for shifting the carrier-block and the inner folder-section upon release of said latching means.

14. The combination with the stitch-forming mechanism of a sewing machine, of a hem-folder disposed in advance of said stitch-forming mechanism comprising a base-plate, an outer folder-section secured upon said base-plate, a shiftable carrier-block mounted upon said base-plate for movements substantially crosswise of the line of seam-

formation, an inner folder-section supported for lateral movements with respect to and with said carrier-block, means for latching said carrier-block in the operative position 5 of the inner folder-section, a work-supporting apron sustained by said carrier-block, a spring for shifting said carrier-block in one direction upon release of its latching means, a slide-bar mounted upon said base-plate en- 10 gageable with said carrier-block, treadle-operated means engageable with said slide-bar for returning the carrier-block into latched position, and supporting means for said base-plate permitting the swinging of said folder 15 from its operative position.

In testimony whereof, I have signed my name to this specification.

RUDOLPH J. SAILER.
